UNITED STATES PATENT OFFICE.

JOHN KEITH REID, OF MONTREAL, CANADA.

SPIKE-DRAWING TOOL.

SPECIFICATION forming part of Letters Patent No. 696,844, dated April 1, 1902.

Application filed September 20, 1901. Serial No. 75,983. (No model.)

To all whom it may concern:

Be it known that I, JOHN KEITH REID, of the city of Montreal, in the district of Montreal and Province of Quebec, Canada, have 5 invented certain new and useful Improvements in Spike-Drawing Tools; and I do hereby declare that the following is a full, clear, and exact description of the same.

My invention has for its object to provide 10 means whereby railway-spikes can more easily be drawn and without damaging either the surface upon which the rail rests or the rail itself.

The invention may be said briefly to consist 15 of a drawing device adapted to fulcrum upon the rail and when worked draw the spike continuously in a straight line with the spike to be drawn.

More specifically speaking, my improved 20 spike-drawing tool consists of a standard adapted to rest upon the head of a rail and having a segmental drum fulcrumed thereto and provided with a lever integral therewith and projecting radially therefrom, while a flexible 25 length is hung from said lever adjacent to said drum and has a device at its lower end for connection to the spike to be drawn, these parts being disposed relatively to one another to have the periphery of the drum intersect a vertical 30 line running through the spike to be drawn.

For full comprehension, however, of my invention reference must be had to the accompanying drawings, in which like symbols indicate the same parts, and wherein—

35 Figure 1 is a side elevation of my improved drawing-tool. Fig. 2 is a face view thereof, and Fig. 3 a plan view.

The standard of my improved spike-drawing tool consists of a plate *b*, having a hook *c* 40 at its lower end, and the space within said hook conforming to the cross-section of the rail-head. The drum *d* is fulcrumed concentrically thereof upon a pin *e*, projecting through a pair of flanges *f*, integral with the 45 interior of said drum, while a pair of nuts *g* retain said drum against displacement longitudinally of the pin. The perimeter of the drum is cut away between these flanges to accommodate the standard. A lever-arm *h* 50 is formed integral with the perimeter of the drum in line with said flanges, and the portion thereof abutting the drum is formed

with a bearing *i*, in which a pin *j* is rigidly set and has its ends projecting across the perimeter of the drum. The ends of two lengths *k* 55 of band-chain are connected, respectively, at their upper ends to the ends of said pin and the lower or depending ends to the upper ends of a pair of jaws *l*, pivoted together, as at *m*, these jaws being when their upper ends are 60 drawn upon adapted to grip the head of the spike.

This drawing-tool may be used in connection with any form of rail other than that indicated at *n*, while to facilitate the working 65 thereof the lever-arm can be made hollow and the end of a wooden handle *o* fitted thereinto.

The drum being concentric of the fulcrum of the lever and the fulcrum being in vertical line with the web of the rail, upon the jaws 70 being caused to grip the head of the spike and the outer end of the lever raised the band-chain will be wound upon the drum and caused to constantly draw the spike in the line of the spike itself, while the strain of the operation will be exerted entirely upon the head 75 of the rail.

What I claim is as follows:

1. A spike-drawing tool comprising a standard consisting of a single vertical plate adapted to rest upon the top of the rail and having a hooked lower end to clip the head of said rail; a segmental drum having its perimeter cut away midway of its axial length to straddle said plate; means for fulcruming said segmental drum to the upper end of said plate concentrically of said drum; a lever-arm formed in one with and projecting radially from said drum in line with one end of the cut-away portion of said drum; a pair of flexible 80 lengths one on each side of said lever and carried by and depending from said lever at the point at which it abuts said segmental drum; and a pair of pivotally-connected gripping-jaws hung from the lower ends of said flexible lengths, substantially as described 85 and for the purpose set forth.

2. A spike-drawing tool comprising a standard consisting of a single vertical plate adapted to rest upon the top of the rail and having a hooked lower end to clip the head of said rail; a segmental drum having its perimeter cut away midway of its axial length to straddle said plate; a pair of flanges one on each 90

side of said plate and integral with the interior of said segmental drum and fulcrumed to the upper end of said plate concentrically of said drum; a lever-arm formed in one with 5 and projecting radially from said drum in line with one end of the cut-away portion of said drum; a pair of flexible lengths one on each side of said lever and carried by and depending from said lever at the point at which it 10 abuts said segmental drum; and a pair of piv-

totally-connected gripping-jaws hung from the lower ends of said flexible lengths, substantially as described and for the purpose set forth.

In testimony whereof I have affixed my signature in presence of two witnesses.

JOHN KEITH REID.
